UNITED STATES PATENT OFFICE.

NIELS C. BRONDERSLEV, OF MINDEN, NEBRASKA.

LEAF-SPRING OILER.

1,253,139.

Specification of Letters Patent.

Patented Jan. 8, 1918.

Application filed June 6, 1917. Serial No. 173,237.

To all whom it may concern:

Be it known that I, NIELS C. BRONDERSLEV, a citizen of the United States, residing at Minden, in the county of Kearney and State of Nebraska, have invented new and useful Improvements in Leaf-Spring Oilers, of which the following is a specification.

This invention relates to lubrication, and 10 more especially it is a device for oiling the leaves of vehicle springs, particularly those used on automobile wheels. It is well known that the leaves used in a spring employed in a high-priced automobile which is 15 otherwise quiet, sometimes screech to the discomfort of the passengers and driver. Devices called leaf-spring oilers have been devised for attachment to such springs whereby a small amount of lubricant is 20 constantly fed to the leaves thereof to prevent this squeaking. My invention relates to this class of attachment, and its primary object is to clip the attachment to the spring in such a manner that it will not become lost 25 off and will not creak. This object is carried out by the specific construction of parts hereinafter more fully described and claimed and as shown in the drawings wherein:—

30 Figure 1 is a perspective view of part of a semi-elliptical spring with this attachment applied.

Fig. 2 is a transverse section on an enlarged scale, taken on about the line 2—2 of 35 Fig. 1.

Fig. 3 is a plan view of the blank of felt or other absorbent before it is put in place.

Fig. 4 is a still further enlarged detail of the oil cup.

40 Fig. 5 is a sectional view of a modification.

We are not concerned with the shape of the spring S, nor its details of construction except that it is made up of leaves, and of 45 these we are interested only in the uppermost which I have lettered L in the drawings. In Fig. 1 the attachment is shown as applied to the inner side of a semi-elliptical spring, but it is obvious that it could 50 be applied to outer or upper side of a full-elliptical spring. Its point of attachment is immaterial but by preference it is placed where its sides extend down past several of the leaves as shown.

55 The casing is of substantially inverted U-

shape and is of channeled metal. It comprises a top plate 1 and two side arms 2, and there are flanges 3 at both sides of the plate and down both edges of the arms. Into the casing is placed an absorbent such 60 as felt, the blank of which is illustrated at 4 in Fig. 3, which view shows that it is provided near its center with a long slot 5. This absorbent is somewhat thicker than the width of the flanges so that when in place 65 it projects beyond them toward the interior of the casing, and obviously it bears against the edges of the several leaves of the spring. The oil cup, whose details are best seen in Fig. 4, comprises a tubular body 7 whose 70 lower end is reduced at 8 and whose upper end rises through a hole in the top plate and above the same and is threaded for the reception of a binding nut 9. While the internal construction of this oil cup is not 75 essential, I will state that as shown it comprises a bore having an expansive spring 10 and an outlet opening 11 from one side of its lower end, the upper end of the bore being reduced as at 12. Upon the spring 80 and beneath the reduced end stands a ball 13, normally closed upward against the reduced end so as to keep out dust and dirt. When the tip of an oil can is inserted 85 through the end 12, the ball is depressed, oil is poured into the cup, passes the ball and through the spring, and flows out the outlet 11 onto the absorbent 4.

A striking feature of my invention is the use of a retainer or clip for holding the attachment on the upper leaf L of a spring. 90 This retainer is made of spring metal, and it has a flat body 20 with its ends 21 turned down and bent inward slightly at 22 so as to hook around the edges of the leaf L and 95 between it and the next adjacent leaf. Through the center of this retainer is an opening 23 into which the reduced end 8 of the oil cup is passed and beneath which it is upset or riveted.

When now all parts are assembled, after the felt has been put into the casing or housing the retainer and oil cup are inserted and borne upward, and the body of the oil cup is passed through the slot 5 in the absorbent 105 and upward through a hole in the top plate 1, and the nut 9 applied. Tightening up on this nut draws the parts together, and draws the retainer or clip upward so as to hold the absorbent against the top plate and between 110

its flanges, and thereafter a few additional turns given to the nut 9 raises the center of the clip or retainer while its remaining portion is held from rising by contact with the face of the absorbent. The result is that the body 20 of the retainer is caused to be arched at its center so that its ends are canted inward and the extremities 22 are forced under the leaf L so that the whole is clipped upon the leaf quite forcibly and held against slipping. In the application of this device to a spring, before tension is applied by setting up the nut 9 the ends 21 of the retainer may be passed astride the edges of the leaf L and moved thereon with comparative ease; and after the attachment is brought to the point of use, setting up the nut arches the retainer as described and throws its extremities inward with the result that it clips the edges of the leaf L in the manner already set forth. Therefore the attachment can not slip or creep, and will not get out of place or become lost off the spring. From time to time oil is introduced into the oil cup and flows down the absorbent, and as will be clear this oil is fed slowly to the edges of the several leaves of the spring so that the latter will not squeak. I do not wish to be limited further than as set forth in the claims below, and the proportions, sizes and materials of parts are otherwise unimportant.

In the modification shown in Fig. 5, the same casing, retainer, and absorbent 4 with its slot 5 are employed; but the top plate 1 of the casing is pierced with a hole 11' over the slot, and underlying this hole and working within said slot is a leaf spring 10' whose normal tendency is to close the hole. However, when an oil can is brought into use and its tip inserted through the hole as indicated in Fig. 5, the spring is bent downward and oil may flow past it and through the slot 5 in a manner already described. The tubular oil cup is now replaced by a bolt 7' passing through the parts and having its lower end 8' reduced and upset or riveted inside

the retainer, and a nut 9' engages the threaded upper end of this bolt and bears on the top plate 1 to hold all parts in close contact.

What is claimed as new is:—

1. The herein described leaf spring oiler comprising a sheet-metal body U-shaped in cross section, bent into an upper portion to 55 overlie this spring and two depending arms to pass by the edges of the several leaves thereof, all portions having side flanges, an absorbent sheet mounted within said body and thicker than the width of said flanges, a 60 retaining plate of spring metal underlying the upper portion of said absorbent and having its ends bent downward and its extremities turned inward, an oil cup whose body passes through the top plate of said body 65 portion and the upper part of said absorbent, whose lower end is secured to the center of said retainer, and whose upper end is externally threaded, and a nut on said threaded end for drawing the oil cup and 70 the center of the retainer upward, whereby the retainer is arched and its ends canted inward, for the purpose set forth.

2. The herein described leaf spring oiler comprising a sheet-metal body U-shaped in 75 cross section and bent into an upper portion to overlie the spring and two depending arms to pass by the edges of the several leaves thereof, all portions having side flanges, an absorbent mounted within said 80 body and having a slot underlying the top plate of its upper portion, said plate having means for admitting a lubricant to the slot, a retaining plate of spring metal underlying the absorbent and having its ends bent 85 downward and their extremities turned inward, and connecting means passing through the top plate, the slot in the absorbent, and the retaining plate and provided with devices for putting it under tension, for the 90 purpose set forth.

In testimony whereof I affix my signature.

NIELS C. BRONDERSLEV.
